(57) **CLAIM**

The ornamental design for a LCD monitor, as shown and described.

DESCRIPTION

FIG. 1 is a front, top, right-side perspective view of a LCD monitor showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, right side isometric view of the LCD monitor of FIG. 1 in use; and,

FIG. 9 is another rear, and right side isometric view of the LCD monitor of FIG. 1 in use.

The broken lines are shown in FIGS. 8 and 9 for illustrative purposes only and form no part of the claimed design.
